CHRISTMAS TREE ORNAMENT

Ely S. Margolis, New York, and Hilbert A. Wachtel, White Plains, N. Y.

Application November 2, 1948, Serial No. 57,924

3 Claims. (Cl. 41—10)

1

The present invention is directed to ornaments, more particularly to a type of ornament which is adapted to be introduced at the top of a Christmas tree.

Ornaments for such a general purpose have long been known and used. One such ornament consisted of a series of wires with beads, tubes and hollow bulbs threaded thereon, the wires being linked together and fastened to give an ornamental structure of considerable complexity. Such an ornament was quite expensive to produce and the decorative effect was not all that is desired since it was impossible to provide any lighting for the ornament. In another ornamentation of the same type, there was provided a coil of wire which was intended to be placed over the tip of the tree and the opposite end of said wire was enclosed within the ornament structure by a relatively complicated arrangement. Provision was made for a lamp within the ornament and it included a socket which was made part thereof and was permanently secured thereto. This device was also cumbersome and not entirely satisfactory in that it could not be securely fastened to the tip of the tree.

The present invention is intended and adapted to overcome the difficulties and disadvantages inherent in devices of the type described, it being among the objects of the present invention to provide an ornament adapted for use on Christmas trees which is simple and compact and which is highly ornamental.

It is also among the objects of the present invention to provide a unitary structure of ornament, base, lamp holder and mounting means, made from plastic materials, in a single operation and being transparent or translucent.

It is still further among the objects of the present invention to provide a simple type of mold which is adapted to form the ornament in a single operation without the necessity of removable cores or the like.

In practicing the present invention, there is provided a two-part mold, one of the parts being hollowed to accommodate the molded ornament itself and the other being correspondingly convex in order to form the hollow back of the ornament. The two parts of the mold are provided with extensions of such form that they cooperate to provide a hollow depending member or tube, preferably tapered and extending down from the bottom of the ornament. The tube is in sections with alternate openings on opposite sides thereof. The mold is also provided with an element which makes provision for a laterally extending holder at the back of the ornament just

2

above the tube. The lamp holder has a key-shaped slot, whereby a lamp in its socket and having connecting wires may be slipped into the narrow portion of the slot and seated in the circular portion to firmly hold the lamp in place and centrally located with respect to the ornament.

In the accompanying drawing constituting a part hereof, and in which like reference characters indicate like parts,

Fig. 1 is a front elevational view of a Christmas tree ornament made in accordance with the present invention, the ornament here being shown as a star;

Fig. 2 is a side elevational view thereof;

Fig. 3 is a fragmentary perspective view looking up from below and showing particularly the structure and relative arrangement of the tube and the lamp holder; and

Fig. 4 is a fragmentary cross-sectional view taken along the line 4—4 of Fig. 1.

As shown in the drawing, the ornament consists essentially of a star 1 of relatively large size, having in the center thereof a second star of smaller size and extending forwardly beyond star 1. Each of the stars may be provided with ribs or irregularities or facets and the material of construction may be transparent or translucent. Thereby when a lamp is placed behind the ornament, various refraction and reflection effects are obtainable.

The back 3 of the ornament is hollow and the edges 4 thereof are in a single plane, which is approximately the meeting plane of the two halves of the mold. The two lower points 5 and 6 of the star meet at the apex 7 of an angle, from which point a tapered tube 8 extends downwardly. The tube has cut-out portions 9 and 10 on one side of plane 4 and 11 and 12 on the opposite side thereof. Openings 9 and 10 are staggered with respect to openings 11 and 12. As a result of such cut-out portions or openings, there results a pair of side bars 13 and 14 in line with edges or plane 4 and constituting means for securely anchoring portions 15 and 16 on one side and portions 17 and 18 on the other side thereof.

Extending from point 19 just above the top of tube 8 is a lateral holder 20 having a circular opening 21 therein and a slot 22 communicating therewith. Opening 21 and slot 22 constitute a key hole slot. Opening 21 is to one side of tube 8, as more particularly shown in Fig. 3. This allows a wire to extend up to opening 21 without interfering with the mounting of the ornament on the tip of the tree.

Any suitable plastic material may be used for

producing the ornament, as for example, cellulose acetate compositions, vinyl resins and many others. The material, usually in the form of a powder, is placed in a suitable chamber in a press containing the mold and subjected to heat and pressure, causing the material to flow and fill the mold cavity, thus forming the ornament and all of the associated elements in a single operation. The mold is then opened, exposing the molded ornament, which may be ejected as usual. No cores are necessary and therefore, the cost of the mold is relatively low.

Because of the character of tube 8 with the various openings of relatively large size therein, the ornament may be easily placed over the tip of a tree, allowing said tip to enter into the tube to the very end thereof. The leaves of the tree extend out through the openings in the tube and form a firm anchorage of the ornament onto the tree. In prior structures, considerable difficulty was encountered in holding the ornament without danger of accidental displacement. Because of the key hole slot in the holder, a lamp which may be in series with a complete string of lamps may be readily inserted by passing the connecting wires through slot 22 with the lamp in its socket above holder 20 and it is then lowered into opening 21 where it is firmly held without any danger of falling out or accidental removal. Because of the fact that a single operation is sufficient to form the entire structure, the ornament is extremely cheap to manufacture, while possessing a very attractive appearance. The transparency and the ornamentation contribute to a brilliant effect when a lamp is placed behind the ornament.

Although the invention has been described setting forth a single specific embodiment thereof, such embodiment was intended to illustrate the invention and not to limit it. Various changes in the details of construction may be made within the spirit of the invention. For instance, tube 8 need not be circular but may be angular and a cross-section may be square, octagonal, triangular, or any other desired shape. While a tube tapered as shown is preferred, this is not essential in all cases and the tube may be of uniform diameter throughout, if desired. Ornament 1 need not be a star but may be of any other character and it may be free from decorative effects or may be embellished as desired.

These and other changes in the details of the structure may be made within the spirit of the invention as described, and the invention is therefore to be broadly construed and not to be limited except by the character of the claims appended hereto.

We claim:

1. An ornament comprising an ornamental body at least partly translucent, a support formed integrally therewith, said support being tubular and depending from the lower edge of said body,

said support consisting essentially of a series of substantially semi-cylindrical sections which are staggered and oppositely disposed with substantially semi-cylindrical openings opposite each said section, said sections being joined together along a longitudinal line, a bracket at the upper end of said tube and integral with said body and tube, the plane of said bracket being substantially at right angles to the axis of said support and having a key-hole slot therein to receive a lamp base for holding a lamp behind said body to illuminate it.

2. An ornament comprising an ornamental body at least partly translucent, a support formed integrally therewith, said support being tubular and depending from the lower edge of said body, said support consisting essentially of a series of substantially semi-cylindrical sections which are staggered and oppositely disposed with substantially semi-cylindrical openings opposite each said section, said sections being joined together along a longitudinal line, a bracket at the upper end of said tube and integral with said body and tube, the plane of said bracket being substantially at right angles to the axis of said support and having a key-hole slot therein to receive a lamp base for holding a lamp behind said body to illuminate it, said body, support and bracket being of a single piece of molded plastic material.

3. An ornament comprising an ornamental body at least partly translucent, a support formed integrally therewith, said support being tubular and depending from the lower edge of said body, said support consisting essentially of a series of substantially semi-cylindrical sections which are staggered and oppositely disposed with substantially semi-cylindrical openings opposite each said section, said sections being joined together along a longitudinal line, a bracket at the upper end of said tube and integral with said body and tube, the plane of said bracket being substantially at right angles to the axis of said support and having a key-hole slot therein to receive a lamp base for holding a lamp behind said body to illuminate it, said body, support and bracket being of a single piece of molded plastic material.
